(57) **CLAIM**

The ornamental design for a mobile device pocket with ring stand, as shown and described.

DESCRIPTION

FIG. 1 is a perspective view of a first embodiment of a mobile device pocket with ring stand showing my new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof;

FIG. 7 is a bottom plan view thereof;

FIG. 8 is a perspective view thereof, shown in an alternate configuration; and

FIG. 9 is a perspective view thereof, showing the article in use.

FIG. 10 is a perspective view of a second embodiment of a mobile device pocket with ring stand showing my new design;

FIG. 11 is a front elevational view thereof;

FIG. 12 is a left side elevational view thereof;

FIG. 13 is a right side elevational view thereof;

FIG. 14 is a rear elevational view thereof;

FIG. 15 is a top plan view thereof;

FIG. 16 is a bottom plan view thereof;

FIG. 17 is a perspective view thereof, shown in an alternate configuration; and,

FIG. 18 is a perspective view thereof, showing the article in use.

The broken lines bordering the edge of the mobile device pocket represent stitching that forms part of the claimed design. The dot-dash broken lines depicting a portion of the ring stand in embodiment 1 represents portions of the article that forms no part of embodiment 1. The dot-dash broken lines depicting environment in FIGS. 9 and 18 form no part of the claimed design.

1 Claim, 8 Drawing Sheets
